DESIGN FOR A DUPLICATOR

Ferdinand Nigra, San Francisco, Calif.

Application March 6, 1937, Serial No. 68,047

Term of patent 7 years

To all whom it may concern:

Be it known that I, Ferdinand Nigra, a citizen of the United States and a resident of San Francisco, in the county of San Francisco, State of California, have invented a new, original, and ornamental Design for a Duplicator, of which the following is a specification, reference being had to the accompanying drawing, forming part thereof, wherein

The figure is a perspective view of a duplicator showing my new design. The opposite side of the duplicator is substantially the same in appearance as the side disclosed.

I claim:

The ornamental design for a duplicator substantially as shown and described.

FERDINAND NIGRA.
